UNITED STATES PATENT OFFICE.

SYLVAIN LOUIS RAVIER, OF PARIS, FRANCE.

WORKS SUCH AS RETAINING-WALLS, PIERS, AND WHARVES.

1,270,659.

Specification of Letters Patent. Patented June 25, 1918.

Application filed February 24, 1916, Serial No. 80,142. Renewed April 18, 1918. Serial No. 229,414.

To all whom it may concern:

Be it known that I, SYLVAIN LOUIS RAVIER, a citizen of the French Republic, residing at Paris, France, have invented 5 certain new and useful Improvements in Works Such as Retaining-Walls, Piers, and Wharves, of which the following is a full, clear, and exact specification.

This invention relates to improvements 10 in the method and means of reinforcing retaining walls and piers.

The object of the invention is to provide 15 simple and economical means for reinforcing banks without undue digging or removal of the bank to be strengthened.

The invention also comprehends improvements in the features to be hereinafter described and particularly pointed out in the claims.

20 In the drawings:

Figure 1 is a vertical section of a bank illustrating one application of the invention.

Fig. 2 is a top plan view of the same.

25 Fig. 3 is a view similar to Fig. 1, but illustrating another form of the invention.

Fig. 4 is a top plan view of the form shown in Fig. 5.

30 Fig. 5 is a view similar to Fig. 1 of a still further form of the invention.

Fig. 6 is a detail vertical section of a modified form of pile.

In carrying out my invention, I first drive a plurality of interlocking piles 1, 35 adjacent the face of the bank 2 of the stream, as shown in the drawings. The piles may be of any suitable interlocking type, and as shown in Figs. 1 and 2, they comprise inner and outer sets 3 and 4, each 40 having end flanges 5. The flanges 5 of the outer set of piles 3 fit over the flanges of the inner set of piles 4, as clearly shown in Fig. 2.

The piles 7, shown in Figs. 3 to 6, are of 45 the reinforced concrete type, the invention being applicable to this form of pile, as well as the metal piles shown in Figs. 1 and 2.

Referring specifically to Figs. 1 and 2, the piles of the set 3, are each formed with 50 a series of openings 8, through which tubes 9 are passed. These tubes extend at an incline with reference to the vertical piles and are each provided with a head 10, which engages the front faces of the piles. The

tubes are open at their inner ends and may 55 be perforated, as indicated at 11. After the tubes are forced through the openings and into the earth, they are filled with concrete. The concrete is forced through the perforations 11, and out the open bottom, which 60 with the frictional engagement of the walls of the tubes and the earth, form anchors. These anchoring members hold the outer set of piles in place, and because of the interlocking flanges, the inner set of piles 4 65 are held against outward movement.

The tubular members 15, shown in Fig. 3, are formed with a reduced portion 16, provided with flanges 17, beveled on their inner ends at 18. In this form of the invention, the head 19 is embedded in the concrete 20 of the reinforced pile, and when in place the flanges serve to act with the concrete as an anchor to hold the piles in place. 70

In Fig. 5 I have shown a tube 21, embedded in the concrete of the pile, and a pipe 22 which extends above the surface of the stream. By this means, the tube, after being driven into the earth, can be filled with concrete above the water. As the concrete is introduced tamped, the pipe is withdrawn. 75

The piles may be provided with enlarged portions 23 at the points where the openings are formed, which form seats for the 80 heads of the tubes, as shown in Fig. 6.

In use I prefer to drive the piles without removing the earth at the front. When the piles are driven down sufficiently, the earth in the stream at the front of the piles is removed to a point below the topmost openings. Then a tube is driven into the earth by any suitable means. For instance, a boring tool may be inserted in the tube, and as it makes the hole the tube is forced in place, 90 the earth being withdrawn at the top of the tube during the operation. After the tube is positioned, the concrete is introduced in any approved manner. If desired it may be introduced through the tube 22. After 95 the topmost tube is filled with concrete, the earth at the front of the pile is further removed to expose another opening and the same operation is carried on.

By this improved method and construction of reinforcing piles, it is evident the invention can be economically practised, and that I am enabled to anchor the piles with 100

driven protected concrete members without first removing all the earth at the rear of the structure.

What I claim is:—

- 5 1. The herein described process of strengthening earth walls consisting in driving interlocking piles adjacent the face of the wall of earth to be strengthened, and then driving anchoring members at an inclination to 10 the piles through openings formed in said piles and into the earth in rear of the piles.
2. The herein described process of strengthening earth walls consisting in driving interlocking piles adjacent the face of the wall of earth to be strengthened, then driving tubes through the piles into the wall of earth and at an angle to the piles, and forcing concrete into the tubes to form anchors to hold the piles in interlocked position.
- 15 3. The herein described process of strengthening earth walls consisting in driving piles adjacent the face of the wall of earth to be strengthened, then driving perforated tubes through the piles into the wall of earth and at an angle to the piles, and forcing concrete into the tubes and through the perforations to form a plurality of concrete projections on the tube.
- 20 4. The herein described method of strengthening earth walls of streams consisting in driving a plurality of interlocking perforated piles adjacent the front face of the wall of earth to be strengthened, removing the earth from the front of the piles to the 25 first perforation therein, inserting a tube through said exposed perforation and into the earth wall, inserting another tube through the first mentioned tube and feeding concrete through the second mentioned tube to the first mentioned tube and withdrawing the second mentioned tube as the concrete fills the first mentioned tube, further

removing earth from the front of the piles, and inserting tubes filled with concrete in 45 other of the perforations in the piles.

5. The herein described method of strengthening earth walls of streams consisting in driving a plurality of interlocked piles formed with openings, removing a portion 50 of the earth from the front of the piles, driving an inclined anchoring member through the opening exposed by the removal of the earth and into the earth in rear of the piles, subsequently removing a 55 further portion of the earth in front of the piles to expose other openings, and subsequently driving other inclined anchoring members through the openings and into the earth in rear of the piles.

6. In wall strengthening means, the combination of a plurality of substantially vertical piles adjacent the face of the wall of earth to be strengthened, said piles having openings, and tubes driven through the 65 openings and into the wall of earth in rear of the piles, said tubes being filled with concrete to form anchors for the piles.

7. In wall strengthening means, the combination of a plurality of substantially vertical piles adjacent the face of the wall of earth to be strengthened, said piles having openings, and headed perforated tubes driven through the openings and into the wall of earth in rear of the piles, said tubes being filled with concrete which projects 70 through the perforations in the tubes and forms anchors for the piles.

Witness my signature this 8th day of February, 1916.

SYLVAINE LOUIS RAVIER.

In presence of—

CHAS. P. PRESSLY,
ANGE BERTHYIN.
